FREDERICK DEACON MARSHALL, OF WEYBRIDGE, ENGLAND.

GAS AND COKE, PLANT APPARATUS.

Application filed April 10, 1926. Serial No. 101,073.

This invention relates to apparatus for simultaneous production of carbonaceous gas and water gas.

In the accompanying drawings illustrating the principle of this invention in the best mode now known to me of applying that principle.

Fig. 1 is a vertical, central section of the retort structure at line 1—1 of Fig. 3 showing a pair of top feed screws in elevation and illustrating by arrows the direction of fuel under carbonization and by other arrows the upward ascent of gas. The view also shows coke in the process of discharge from the under end of the retort.

Fig. 2 is a transverse section of the upper feeding casing structure at line 2—2 of Fig. 1 and shows the feed casing with a charge of hydrocarbonaceous material, such as bituminous coal, within the casing.

Fig. 3 is a transverse section through the retort casing proper and shows the relations of the cells for containing material to be carbonized, to the gas tubes or ducts.

Figs. 4 and 5 illustrate another form of the invention, Fig. 4 being a vertical central section of the retort structure at line 4—4 of Fig. 7 and Fig. 5 being a vertical central section at line 5—5 of Fig. 4.

Fig. 6 is a transverse section of the upper feed casing and with charge in place, at line 6—6 of Fig. 4; and

Fig. 7 is a transverse section of the retort at line 7—7 of Fig. 4.

Fig. 8 illustrates another form of cellular retort casing proper construction and wherein material to be carbonized is shown in place in vertical cells and wherein also gas ducts are shown.

Fig. 9 is a cross section at line 9—9 of Fig. 1 and shows the location of the gas outlets at the upper end portions of the gas tubes.

Fig. 10 is a vertical, central section of the shaft supporting gland structure with a feed screw shaft partially shown.

Fig. 11 is a cross-section of what is shown in Fig. 10 at line 11—11 of Fig. 10.

Figs. 12, 13 and 14 are views of a feed screw shaft reducing gear.

Fig. 15 is an elevation of plant apparatus embodying this invention.

Fig. 16 is an elevational plan of what is

shown in Fig. 15, partly in cross-section at line 16—16 of Fig. 15.

Fig. 17 is a diagrammatic view of flow sheet illustrating the method involved in the use of the apparatus illustrated in Figs. 15 and 16. It also contains diagrammatic illustrations of resultant products.

The illustrated apparatus is one form of apparatus for working my new method of mixed carbonaceous gas and coke production not herein claimed, but claimed in my application Ser. No. 101,074, filed April 10, 1926, and of even date herewith.

In the accompanying drawings, 1 is the retort casing proper wherein the material to be gasified is contained. 2 is the head casing; 2^a are a pair of non-contacting feed screws which may either overlap or receive the peripheries of the helices just clearing each other; 3 are the gas ducts shown as connected by cross webs *x* to the inner sides of the retort casing. It will be noted that these ducts have gas escape openings at their upper end portions. Their tops are closed but they are open at their under ends. The charge receiving cells 3^a are open both at top and bottom. The cell walls are indicated by 3^b. All the duct or passageway walls are connected by webs *x*. The retort casing 1 is enclosed by a spaced apart combustion or heating chamber wall 3^c.

To prevent coal or other material passing down the gas ducts, the open top of each is fitted with a cover or stopper S above the gas duct escape slots *s*.

4 is the expansion joint shown in this case at the bottom end of the retort casing and formed by an annulus which encloses the lower end of the retort casing 1 with a space between the exterior of the casing wall and the interior wall of the annulus. This space is filled with a suitable packing 4^a; 5 is the coke receptacle which forms the framework of balanced flap doors 6 shown attached to a rocker shaft 6^a, the ends of which are provided with counterweights 7 for closing and maintaining the doors in a closed position. 8 are the twin screw shafts; 9 is the gas outlet; 10 is the inlet for material under course of treatment; 11 are gas-tight supporting glands from which the screws depend. 12 is the turning gear which has been spe-

cially designed for the present purpose and which is connectible with an electric motor M by which a motor speed of 1000 revolutions per minute is reduced by means of the arrangement to give the feed screws a rotational speed of from 6 to 10 revolutions per hour.

The cross section for a retort 1 shown in Fig. 8 is merely another form of the cellular construction above described.

According to my present invention, the plurality of screws do not pass through the body of the retort casing the same as described in my co-pending application Ser. No. 101,074 filed April 10, 1926, but the screw propellers are situated in a separate casing which is attached to the upper end of the retort casing proper which latter casing is heated by the described method of co-pending application Ser. No. 101,074, filed April 10, 1926, for the purpose of carbonizing, gasifying and coking the material passing through the retort; whereas the casing containing the screws is situated outside the zone of heat.

The short screws in the upper, non-heated casing 1 act as collectors of the material and propellers of the same to force the material which is fed by these screws or propellers downwards into and through vertical ducts of the heated body of the retort casing proper or lower section, where the material undergoes carbonization or gasification, said lower section is the heatable, coal distillation structure of the apparatus.

The experience has been gained by the inventor to effect low temperature carbonization at a temperature ranging between 900°-1200° Fah. that the thickness of the material under the process of carbonization or gasification must not exceed four and one-half inches and that provision must be made for applying this heat to all four sides of the material.

As the density of the resultant coke from the material is entirely due not to temperature but to the expansion of the material while in a semi-carbonized or semi-plastic condition and as this expansion exerts a great force, provision must be made that the walls of the ducts through which the material is forced by the pressure and also the screws to travel are of sufficient strength to withstand the great pressure.

The bore of the upper head casing 2 and of the lower carbonizing section is practically the same, and when both are soon empty they will represent a true bore from end to end of both sections when fitted together.

The bore of the upper section is filled by the two screws which can be of the overlapping but non-contacting type, or the screws need not overlap but just clear each other.

The bore of the lower casing or retort

proper is, however, sub-divided in horizontal and vertical alignment by a number of radically or transversely disposed and the lengthwise extending webs *x* and integral duct walls, but so that the ducts enclosed by the metal do not exceed approximately four and one-half inches in cross sectional dimension. The rate of the flow of heat through coal is about one inch per hour and practically and commercially considered, it is highly desirable that the cross section of the ducts should not be over about four and one-half inches along the intermediate portions of the ducts, where the active distillation of the coal takes place, adjacent and above the lower portions of the ducts where the coking is progressively effected.

These radial and transverse webs are an integral part of the retort casing itself, being cast as part of the same; and by reason of the conductivity of cast iron, and by molecular affinity of the iron the heat applied to the exterior of the retort is conducted through all the transverse and radially disposed members and is so imparted to the material which fills the retort cells or ducts during its passage through the same.

The said cells or ducts need not necessarily be of the same cross-sectional area or shape as they may be so shaped as to produce slabs of coke, bearing always in mind the four and one-half inches condition; or they may be disposed in honeycomb (Fig. 8) form for the purpose of producing a briquette like form of coke.

The said members or walls forming the cells or ducts are located between the outer casing and inner hollow gas ducts for aiding the rapid withdrawal of the evolved gases from the retort, and have nothing to do with the heating of the same.

During the evolution of the gases, the gas outlet is under the influence of minus atmospheric pressure owing to the action of the gas exhauster, not shown but diagrammatically indicated.

The evolved gases find their way to their outlet through the centres of the charges of material as, owing to the pressure exerted on all sides by the expansion of the charges during carbonization, very little or no gas can find its way up between the outer sides of the charges and the inner surfaces of the containing cells or ducts.

The coal and gas ducts being open at each end are naturally susceptible to the exhauster suction on the interior of the retort generally and as the evolved gases seek to leave the centres of the charges by the path offering the least resistance, it is open for these gases to leave partly direct through the upper portion of the charges or partly through the lower ends of the gas ducts, and the arrows in the drawing show the approximate paths the

gases take. The coal or distillation ducts are open at their upper and under ends. The gas ducts are open at their under ends, and though closed at their upper end openings by 5 members S in order to prevent the coal from being forced down into them and so clogging the ducts, are provided at their upper end portions adjacent the members S with gas escape ports 8.

10 Much value is attached to these ducts as the easier and with less resistance the gases can escape, the chances of their being "cracked" or split up is greatly lessened.

To increase the through-put capacity of 15 the retort, the divisions or webs x in the retort may be disposed in an annular manner and, provided all divisions are connected physically with the outer, inner wall of the retort, the carbonization of the interior columns of 20 material, coal or coke will be as equally well effected as in the outer columns of material, coal or coke.

The power exerted by the co-acting feed screws in the upper casing on the mass of 25 material forced through the lower casing is enormous and provision has to be made to eject the charge of carbonized coke from the casing automatically and continuously before the pressure on the material leads to destructive consequences.

According to the present form of my invention this is effected by the installation, at the lower end of the lower casing or section 1, of a coke box or receptacle within which a pair of 35 flap doors are installed working on hinges; and which, when in a horizontal condition, close the bottom of the superimposed casing in a practically gas tight manner as the edges of the flaps are bevelled to the same angle as 40 the tapering sides of the coke box or receptacle against which they contact, so that the foot of the columns of coke in the casing rest on the flaps which are kept in position by a lever attached to each flap which levers are controlled by weights or springs.

The desired pressure to be exerted by the co-acting screws on the charge of material to force the same through the lower casing, having been ascertained, the levers are weighted 50 accordingly so that when the pressure on the charge reached a certain point the flaps are forced open and a portion of the charge in the form of coke is ejected into the gas-tight box or receptacle below the flaps. When the 55 pressure being relieved, the weight on the levers causes the flaps to return to a horizontal position.

At intervals the coke receptacle is opened and the coke removed during which period 60 the revolution of the co-acting screws may be stopped and the flaps held up to insure against the entering of air into the retort casing.

The design of the flap doors 6 may be varied

and instead of hinging them on their long 65 sides they may be hinged on their short sides in either case being controlled by the outside levers fitted with either weights or springs. The flap doors 6 are merely one form of coke escape control apparatus for also offering a 70 resistance to the downward feeding pressure and load of the coal in its initial condition, in its active distillation and gas evolving condition, and in its progressive coking in the lower portion of each distillation duct. 75

The density of the coke can be varied by the amount of pressure it is subjected to during its formation in the retort and this controllable variation of pressure is another feature of my invention. 80

To take up the expansion of the retort in a vertically longitudinal direction, it is proposed to intervene either between the upper non-heated casing or the lower non-heated section represented by the coke receptacle a 85 loose joint of any desired construction.

Each gland 11 comprises an upstanding, annular capped casing to which the reference 90 11 is applied. The casing has a bottom that is solid except for a central shaft opening 95 through which a shaft 8 extends upwardly through the fixed cover plate 13 of casing 2, and upwardly through the fixed cover 14 of casing 11 for reception of members of the turning gear 12. Within the gland casing, 100 there is at its bottom portion a pair of disc-shaped ball races 15 between which anti-friction balls 16 are located, the shaft passing through the races and upwardly through a piston 17 provided with piston rings 18. The piston is pinned to the shaft by pins 19 and has a length less than the distance between the upper race 18 and the gland casing cover, leaving a clear space 20 into which the piston may ascend on elongation of the shaft due to 105 heat. Each screw is suspended from its piston which normally rests on the upper race. The bottom of the gland casing is provided with a packing p around the screw shaft and the gland as a whole is gas-tight and constitutes a gas-tight, anti-friction screw suspending mechanism that permits endwise movement of the suspended screw. 110

The turning gear or driving mechanism which is fixed on the upper casing cover, although it may be otherwise supported, includes an addition to the gear 12 which is a spur gear, one on the upper end of each screw shaft, an intermediate spur gear 21 in mesh with gears 12. Gear 22 is mounted on the 120 upper end portion of a vertical stub shaft 23 and drives the screw shafts simultaneously in the same direction. Stub shaft 23 also carries a worm gear 24 in mesh with a worm 25 on a horizontal shaft 26 which is provided with a worm gear 27. This worm gear is in mesh with an intermediate worm gear 28 which in turn is in mesh with a worm 29 on 125

the shaft 30 of a motor M. This driving gear serves to reduce a motor speed of about 1000 revolutions per minute to a screw rotational speed of from six to ten revolutions per hour, as above stated.

The stoppers S at the upper ends of the gas tubes are fixed in place, thus preventing entrance of the material into the gas tubes or passageways; but the gas exit ports s are continuously open so that the generated gas may continuously escape therethrough, into the communicating space S' and then to the exit, 9, while the retorting operation is active. The rocker shaft 6^a mounted in openings 15 of the wall of the receiver 5 for coke or other residue of distillation, extends at both ends outwardly of the receiver. Each end has a dependent arm 6^b for reception of one or more removable weights 7, two of which are shown 20 on each arm. The weights may be increased or diminished in number according to the character of the material to be treated. Receiver 5 is practically air-tight and is provided with an opening 5^a through which the 25 residue of distillation may be removed from time to time. The opening is shown provided with a door 5^b.

The approximately flat-sided screw casing having arcuate walls, between each two flattened walls, is a feature of the invention. The arcuate walls are closely adjacent and partially enclose opposed portions of the feed screw helices while the flattened sides, which are opposed to the overlap or overhang of the 35 helices, affords greater space for material being fed than would be the case if the casings were of a cross-sectionally figure-8 contour.

The combustion chamber C is for heat applied during the retorting operation which 40 may be a low temperature operation for which the apparatus is especially intended.

The intake 10 is provided, in practice, with a gas-tight charging device 10^a of any desired construction. The charging device is here- 45 in indicated diagrammatically.

In operation, succeeding initial charging, charge arresting and carbonization, the feed screws may be driven continuously and the charge arresting doors may be continuously 50 opened for either partial momentary interruption of escape, or, for continuous escape, of the coke into the coke box, with the box door closed to prevent inrush of air, all depending on the character of the material 55 treated and the desire of the operator.

The described arrangement for disposition of the descending material in a plurality of relatively small, cross-sectional and relatively thin walled, lengthwise extending ducts 60 and for simultaneous ascent of evolved gas through the corresponding gas ducts, insures a perfection of carbonization or distillation attended by maximum evolution by gas from the material.

Evolution and removal of the gas is continuous. The charging operation may be continuous or intermittent depending on the type of charging apparatus used. The discharge of the coke into the coke box is continuously effected by the automatically intermittent wabbling of the flap doors 6.

In Fig. 5, the gas escape 9 is shown discharging into a diagrammatically illustrated exhauster 9^a. The exhauster connection is sufficient in practice to effect the ascent of gas into the escape 9, notwithstanding the pressure on the charge between the feed screws and flap door. Some of the ascending gas escapes from fissures in the coke and some of it from material M thereabove.

During the working of a water gas generator, as is well understood, the generator is filled with carbonaceous material such as coke and raised to incandescence by means of an air blast, technically called the blow period. When the proper degree of incandescence is reached, the blast or blow is shut off and steam is passed through the heated material, this operation being termed the run period. The interaction between the steam and the incandescent carbon generates the water gas which is a mixture composed principally of carbon monoxide and hydrogen. During the operation of manufacturing water gas, three sources of heat are developed apart from the heat which can be generated by burning the water gas itself. These three sources of heat have heretofore principally been regarded as waste heat and are as follows:—(1) the sensible heat of the blow gas; (2) the heat generated by the combustion of the carbon-monoxide constituent of the blow gas, and (3) the sensible heat of the water gas, and one of the objects of the present invention is to utilize the three aforesaid sources of heat in connection with the distillation of solid carbonaceous or other materials before they are allowed to pass to the chimney or stack.

Experiments have shown that the heat generated or obtained from the three aforesaid sources is sufficient to effect the distillation of carbonaceous materials.

According to one feature of the present invention, the hot blow gas is conveyed from the water gas generator with as little loss as possible of its so-called sensible heat and together with a supply of pre-heated air, is admitted to a combustion chamber composed of refractory material and which surrounds a retort within which a process of low or medium, distillation is to be carried on. A combustible mixture is thus produced wherein the sensible heat of the blow gas is added to the heat derived from the combustion of the blow gas itself.

Another feature of this invention is to employ the hot water gas for steam raising purposes or partial steam raising by passing the

same through a heat interchanger, the heat generated in the heat interchanger being employed, for example, in raising the temperature of the water supplied to the interchanger which water may be employed in an adjacent boiler, for raising steam and at the same time cooling the hot water gas.

As the process of producing blow gas and water gas is intermittent, two water gas generators, may, if desired, be employed for alternate use.

During the blow period of gas generation and owing to the considerable pressure of the air employed for the blast or blow which air passes through the incandescent coke in the water gas generator a quantity of hot ashes, cinders and dust are carried away with the blow gas and normally are deposited in the neighborhood of the generator. Furthermore, the heat of the said ashes, representing about two percent of the heat of the fuel (coke) with which the generator is fed is lost.

According to another feature of the present invention, and in cases where blow gas is ignited in a combustion chamber for the purpose of treating carbonaceous or other materials, the blow gas, before entering the combustion chamber is passed through a so-called cyclone dust arrester. A suitable form of dust arrester consists of a cylindrical chamber with a conical lower part, the gases containing the cinders and dust being caused to enter the upper cylindrical part thereof at a tangent to the periphery of the cylinder, whereby a whirling or centrifugal motion is imparted to the entering gases. Consequently the dust and cinders are thrown against the sides of the chamber and, by gravity, fall to the bottom thereof where they may pass through a pipe or passage into a water sealed tank from which they are raked out from time to time.

According to a further feature of the present invention, and in cases where it is desired to ignite and utilize the blow gas in the aforesaid manner, use is made of the heat of the cinders and dust which pass into the dust extractor to preheat the air required for the purpose of igniting the blow gas. To this end an air inlet pipe is provided which extends axially through the cyclone dust extractor the said air pipe being surrounded by a concentrically mounted pipe or casing through which the blow gas, after the dust and ashes have been separated therefrom passes either to the retort, the boiler or elsewhere. Owing to this arrangement, and on account of the fact that the hot dust and ashes raise the temperature of the parts of the dust extractor to a considerable extent, the temperature of the air is also raised to a considerable extent, the heating operation being further assisted by the sensible heat of the blow gas which may flow along the

exterior of the air pipe until both concentrically mounted pipes enter the combustion chamber of the retort or the like.

Referring to the plant structure, (Fig. 15), 31 is a retort stack or snift valve structure, 32 a water gas generator, 33 a dust extractor and pre-heater, 34 the separated dust escape port of the dust extractor or separator; 35 is an air blower, 36 a motor connected with the blower, 37 the blower discharge pipe, 38 a blow gas duct, 40 a subsidiary air supply duct, the blow gas duct and subsidiary air duct discharging closely adjacent into the combustion chamber C; 41 is the under, vertical conduit leg of an L-shaped conduit the under end of which is open within the chamber of the dust extractor or separator and the upper horizontal leg of which is entrant into the combustion chamber. The subsidiary air pipe 40 extends from the blower discharge pipe 37 into the under portion of the dust separator 33, thence upwardly within and out of contact with the dependent conduit leg 41 and thence horizontally into the combustion chamber, the upper conduit leg 40 forming the air supply duct 40 closely adjacent the closed blow gas duct 39. 42 is the steam run pipe for the water gas generator, 43 the blow gas discharge pipe from the water gas generator into the upper end of the dust extractor 33, pipe 43 entering the dust extractor, which is circular in cross-section tangentially. 44 is the water gas escape pipe from the chamber into a heat interchanger 45; 46 is a conduit leading from the heat interchanger for conveyance of cooled water gas therefrom to the junction of the pipe 46 at 47 with the carbonaceous gas escape pipe 48 that is in connection with the gas escape pipe 9 of the retort apparatus. The dust extractor 33 has an under end, vertical dust and cinder discharge into a water tank 49 or other suitable receptacle.

In the form shown, the steam run pipe 42 to the water gas generator leads from a steam boiler, as a source of steam, which may or may not be in communication with the heat interchanger 45. This heat interchanger is shown as a vertical casing provided with interior water tubes 51 into which cold water is introduced through a supply conduit 52. The temperature of the water in the tubes is raised by the sensible heat of the hot water gas, passed into the casing through the pipe 44 and the heated water in the tubes is conducted to the steam boiler, as hot water or steam through a feed water or steam conduit 53. The coke product P is a hard, dense coke admirably adapted for use in water gas generation. In practice, such coke residue may be economically used in the water gas generator 32.

Referring to the above and also to Fig. 14 and following figures of the drawings, 31 is a chimney stack which in connection with a

water gas plant is termed a "snift" valve. During the so called blow period this is opened by a lever attached to a chain; but during the steam run period, the valve is shut ⁵ so as to retain the heat of the blow in the combustion chamber.

32 is the water gas generator of which any well-known type may be selected, the sequence of operations being practically the ¹⁰ same whichever type of water gas generator be employed.

The fuel required by the water gas generator, viz coke is preferably supplied from the retort to generator 32 which in turn supplies ¹⁵ the necessary heat to the retort to enable it to produce the necessary coke, the relation between the two apparatus items is thus reciprocal.

The coke to the water gas generator is ²⁰ blown to incandescence by the turbine positive air blower 35 which is actuated by motor 36. Air passes to the water gas generator 32 by pipe 37 upwards through the coke charge in the generator, being in its passage con- ²⁵ verted by contact with the red hot carbon into so called blow gases which are a mixture of carbon monoxide (CO) and carbon dioxide (CO₂).

These gases before passing into the combustion chamber 6 surrounding the retort enter the dust extractor 33 wherein, by the centrifugal action of the blast, the ashes, cinders and dust in the blow gases, representing some ³⁰ two percent of the total heat of the fuel supplied to the generator, are absorbed; and the cleansed gases enter the port leading to the combustion chamber through duct 39.

The blow gases would be unignitable unless supplied with a sufficiency of air, preferably ⁴⁰ heated, as the hotter this air supply is the more effective and intense is the combustion of the combustible CO in the blow gases. Consequently, a certain quantity of the air representing the main blow to the water gas generator is tapped off by a subsidiary pipe ⁴⁵ 40 controlled by a valve, the pressure exerted by the turbine blower 35 being sufficient to force this air supply through the pipe 40 which passes through the lower end of the ⁵⁰ gas outlet pipe 41 and extends through the same. Both the main blow gas pipe 39 and the smaller air pipe 40 are entrant into the combustion chamber together, where ignition takes place; the air having picked up the ⁵⁵ heat from the ashes, cinders and dust which are scattered all over the interior of the dust extractor.

Returning to the water gas generator, the blow period as described above being finished, after say four minutes of blow, the valves controlling the blow and likewise the cap of the chimney stack are closed. No valves are shown or described as the working ⁶⁰ of the valves are well known and to explain ⁶⁵ in detail well known operations would un-

necessarily complicate both drawings and explanation.

The blow valves being closed, the valves operating the run (steam run) are opened and steam is admitted by pipe 42 to the generator and travels downwards for four minutes or so.

During the passage of the steam through the incandescent carbon, the same is converted into water gas,—a mixture of half ⁷⁵ hydrogen and half carbon monoxide.

The water gas as it issues through pipe 44 is very hot; its sensible heat being somewhere near 1100° Fah. Temperature of a very large volume of the produced water gas, in order to either raise some pounds of steam or to raise the temperature of cold water to over the boiling point so that this water could be used as feed water to an adjacent steam boiler.

It is necessary to cool the evolved, heated water gas to a normal atmospheric temperature before the same could be usefully employed.

Therefore, to accomplish both the cooling ⁹⁰ of the large quantity of heated water gas and to usefully employ the sensible heat of the same, the heated water gas is passed by pipe 44 into a so-called heat interchanger 45 which is fed by cold water which, coming into contact with the sensible heat of the water gas, is raised to practically the same temperature, allowance being made for radiated and converted heat losses. But by a properly constructed heat interchanger, all the sensible ⁹⁵ heat can easily be removed from the heated water gas and a supply of low pressure steam or water heated to over 212° can be obtained.

On leaving the heat interchanger, the cooled water gas passes by pipe 46 to the pipe junction 47 where it meets and is mixed with the rich coal gas from the retort through the pipe 48 that communicates with the gas outlet 9 of the retort. Such gas through the outlet 9 and pipe 48 is in turn heated and carbonized by the heated blow gases evolved in the water gas generator 32.

In the distillation of hydrocarbonaceous material, the products are a rich coal gas; ammonia vapours; tar oils containing spirits, ¹¹⁵ oils, tar acids of the cresol-phenol types, paraffin wax, pitch containing a very low percentage of free carbon and coke.

The quantity and quality of these products depends entirely on the temperature at ¹²⁰ which the hydro-carbon selected is carbonized in the special retort and one object of the process is to effect carbonization at a temperature which will yield a very rich gas of about 600-800 B. t. u.'s per cubic foot and which ¹²⁵ will produce oil bearing vapours which on being condensed will be of the olefine or aliphatic series of paraffinoids and removed as far as possible from the aromatic or benzoid series, and to effect this result the tem- ¹³⁰

perature within the retort itself must not exceed or considerably exceed some 1400° Fah. as beyond this temperature the benzoid series begin to appear, and if the temperature be raised to the maximum the retorts could stand say 1700° Fah. the objectionable naphthalene series would likewise appear.

The dust laden blow gas enters the dust separator through its circular casing side and discharged interiorly to some extent tangentially causes the dust laden gas to whirl violently, as indicated by arrows, the dust and cinders dropping downwardly through the under outlet port 34 into a water tank. When the coal ducts are filled and the feed screws are in action, the coal or other material is forced into the upper, open ends of the coal ducts and is under constant pressure downwardly to the coke discharge control apparatus. While this apparatus permits, by vibration of the free edges of the flap doors on which the coke initially rests, continuous escape of the coke according to adjustments of the weights 7, the apparatus, nevertheless, offers such a resistance to the downward pressure that the pressure densifies the coke substantially and firm coke is produced. It will be observed that the heatable, metal walls of the coal and gas ducts are integral and serve to conduct exteriorly applied heat to and through the material in the coal ducts; and that there is a plurality of coal ducts subjacent the under end of each feed screw. The integrally and metallically walled, coal ducts are raised to a temperature sufficient to render portions of the coal, as it is forced compressively downward from the upper end portion of the coal ducts, plastic; and in this condition gas is freely evolved, the plastic condition permitting the feed screw pressures to condense and solidify the coke formed in the lower portion of the coal ducts against the flap doors or gates carried by the adjustably weighted, rocker shaft 6^a. When the apparatus is in operation, these flap doors or gates are never closed, but are constantly vibrating and thus permit continuous discharge of the solidified or densified coke which, with all the superincumbent material in the coal ducts, is under continuous downward pressure by the feed screws. The feed screws and their operating mechanism constitute, in effect, a continuously operable pump for the coal or other gasifiable and coke producing material.

In accordance with the present invention, as illustrated, the water gas apparatus, the dust separator and preheater, the air blower, the heat interchanger and the steam boiler, are each a separate unit, all these units being installed spacedly apart from the retort and spacedly apart one from the other. Such installations of these separate units all of which are in the heretofore described conduit rela-

tion one to another and to the retort, not only permit repairs to and the substitution of one unit for another when necessary, without shutting down the remainder of the plant; but also, in a very important sense, permit a regulated control of the water gas apparatus in its working connection with the retort, and such variations in the time and volumes of the water and blow gas supply to the retorting apparatus as may be required under actual working conditions of the gas and coke producing functions of the retort structure.

The coal becomes plastic in a stratum or in strata where it changes into coke. By keeping the in-fed coal and the coking plastic stratum or strata under constant pressure as described, the formation of thin and fragile walled coke cells is prevented and a dense compact coke product obtained. Such a densification is of very great importance to the coke product as it does not break up or give off coke dust as is the case with coarsely cellular coke. Moreover, the constant compression is favorable to evolution of the gas evolving from the coking portion of the coal and from the coal.

What I claim is:

1. In gas and coke making apparatus, the combination of a retort; a combustion chamber forming structure vertically enclosing said retort; a blow gas dust and cinder separator provided with an under outlet for the separated dust and cinders and having an upper, cleansed blow gas discharge port in conduit connection with said combustion chamber; an air blower having an air education outlet in communication with an air pipe; the air pipe extending into, through and out of said separator into said combustion chamber for heating the air passing through said pipe; and a water gas generator in communication with a blow gas pipe; said blow gas pipe, communicating with said separator; said structure, separator, blower and water gas generator being spaced apart one from another.

2. In the combination set forth in claim 1, said air blower being in conduit connection with said water gas generator at a point remote from the connection of said blow gas pipe with said water gas generator.

3. In the combination set forth in claim 1, a heat interchanger; a water gas conduit for transfer of hot water gas from said water gas generator to said interchanger; a water gas conduit leading from said heat interchanger for passage of cooled water gas; the interchanger comprising a casing and interior water tubes; and a cold water supply pipe communicating with said water tubes.

4. In the combination set forth in claim 1, a heat interchanger; a water gas conduit for transfer of hot water gas from said water gas generator to said interchanger; a water gas conduit leading from said heat inter-

changer for passage of cooled water gas; the interchanger comprising a casing and vertical interior water tubes; and a cold water supply pipe communicating with said water tubes and a source of steam; the upper ends of the water tubes being in conduit connection with the source of steam and said source

of steam being in conduit connection with an upper portion of the water gas generator.

Signed at New York city in the county of ¹⁰ New York and State of New York this 12th day of March, A. D. 1926.

FREDERICK DEACON MARSHALL.
